UNITED STATES PATENT OFFICE.

SAMSON BORGNISS, OF PHILADELPHIA, PENNSYLVANIA.

GARTER GRIP.

Application filed March 10, 1926. Serial No. 93,599.

My invention relates to new and useful improvements in a garter grip, and has for its primary object to provide an exceedingly simple and effective device of this character whereby the garter strap may be readily secured to the leg of a wearer.

Another object of the invention is to improve the construction of such devices whereby any protuberances which might interfere with other parts of the wearer's clothing will be eliminated.

A further object of the invention is to so construct the elements of the grip that one will nest within another so that the strain incident to suspending a hose will be distributed over a greater surface of the grip thereby reducing to a minimum the possibility of the parts becoming separated, as well as the likelihood of the parts being bent out of shape or otherwise damaged so that the life of the grip is increased.

A still further object of the invention is to improve the construction of the spring latch and the method of mounting the same. With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1 is a front elevation of a garter, illustrating my garter grip applied thereto.

Fig. 2, is an enlarged plan view of the socket member with a portion broken away and parts shown in section to illustrate details of construction.

Fig. 3, is a longitudinal sectional view thereof.

Fig. 4, is an enlarged plan view of the stud member.

Fig. 5, is a longitudinal sectional view thereof.

In carrying out my invention as herein embodied, 10 represents a garter of any well-known or desired construction, including a pad 11, provided with the usual clasp 12 for attachment to a hose, and a strap 13 usually of elastic material with its fore end looped and provided with an attaching buckle 14.

To the pad 11 is secured a stud member 15 of my improved garter grip by means of stitches 16 running thru the pad and the slot 17 in the leaf 18. With the leaf 18 is formed the integral concavo-convex body 19 having a stud 20 projecting from the convex surface formed by pressing or stamping out the central portion of the body 19 and then pinching an intermediate portion of the pressed-out part to provide a ball-like head 21 and a neck 22.

A socket member 23 is attached to the fore looped end of the strap 13 by threading said strap thru the slot 24 in the leaf 25, said leaf having a lug 26 projecting therefrom, which lug lies within the loop of the garter strap, and limits the swing of the socket member in the looped end of the garter strap. With the wing is formed an integral hood 27 which houses the insert 28. The insert 28 includes a concavo-convex body 29 of such dimensions as to fit over the body 19 of the stud member, whereby the body of said stud member snugly nests within the body of the insert so that their peripheral flanges engage, and any strain on the grip will be distributed about the peripheral flanges of the bodies of the two members.

From the body 29 of the insert is formed a socket 30 by pressing, stamping or otherwise, and this socket has a pair of oppositely disposed slots 31 for the reception of the arms 32 of the spring clip 33, said spring clips being produced from a piece of suitable resilient wire fashioned to provide the arms 32, extensions 34 projecting outwardly at right angles from the arms 32 and a bow 35 between the two extensions 34, the construction of said bow being substantially that of the hood 27 so as to fit within the latter and limit the movements of the spring clips in one direction.

The socket 30 being of the proper dimensions to receive the stud 20 and the arms 32 of the spring clip being disposed across the chamber of the socket, as plainly shown in Fig. 2, when the stud is inserted in the socket, the head 21 thereof of said stud will force the arms of the spring clip away from each other until the stud head passes beyond the clipped arms, when the latter will again move toward each other and engage the neck of the stud thereby preventing accidental withdrawal of the stud member from the socket member.

It is to be understood that the insert 28 fits within the hood 27, where it is secured in any desirable or well-known manner, as by rolling the edge of the hood member 3 over the outer face of the insert, as will be obvious.

Of course I do not wish to be limited to the exact details of construction as herein shown as these may be varied within the 10 limits of the appended claims without departing from the spirit of my invention.

Having thus fully described my invention, what I claim as new and useful is:

1. A garter grip comprising stud and 15 socket members; said stud member including a wing, a concavo-convex body, and a stud and said socket member including a wing, a hood, an insert mounted in the hood and provided with a concavo-convex body and a 20 slotted socket, and a spring clip housed between the hood and insert having arms registering with the slots in the socket, so as to be disposed across the chamber within said socket.
2. A garter grip comprising, in combination, a socket member including a wing 25

provided with a slot, a projection extending from said wing, an integral hood formed with said wing, an insert within said hood, and comprising a concavo-convex 30 body and an integral socket, the latter having oppositely disposed slots therein, a spring clip within the hood including a bow, extensions projecting inwardly from the ends of the bow, and arms projecting from 35 said extensions at right angles thereto for registration with slots in the socket so as to be disposed across the chamber of said socket; a stud member for coaction with the socket member including a wing having a 40 slot therein, an integral concavo-convex body to nest within the body of the insert of the socket member, an integral stud formed from the body of the stud member and fashioned to provide a head and neck, 45 said head being insertable in the socket whereby the arms of the spring clip engage the neck to prevent accidental separation of the two members.

In testimony whereof, I have hereunto 50 affixed my signature.

SAMSON BORGNISS.
